UNITED STATES PATENT OFFICE.

GEORGE H. PHELPS, OF BOSTON, MASSACHUSETTS, ASSIGNOR TO GEORGE FROST COMPANY, OF BOSTON, MASSACHUSETTS, A CORPORATION OF MASSACHUSETTS.

GARTER.

No. 348,627.

Specification of Letters Patent.

Patented Feb. 12, 1907.

Application filed December 8, 1906. Serial No. 346,042.

To all whom it may concern:

Be it known that I, GEORGE H. PHELPS, a citizen of the United States, residing in Boston, in the county of Suffolk and State of Massachusetts, have invented certain new and useful Improvements in Garters, of which the following is a specification.

My invention relates to that class of garters known as "gentlemen's garters," which comprise a band adapted to inclose the leg of the wearer, a clasp adapted for attachment to the hose, and a suspending device which connects the clasp with the band. Letters Patent of the United States have heretofore been granted to me for improvements in this class of garters.

The object of my present invention is to provide an improved leg-band for garters of this class, which, while sufficiently strong to sustain all strains and of such texture and material as to wear well and possessing moderate elasticity and resiliency, shall be softer and less elastic than some heretofore employed, whereby it will exert less pressure upon the leg, will be less harsh when worn next the skin, but will have such flexibility and moderate elasticity and resiliency as to securely cling to the leg under all conditions.

According to my invention I form the leg-band of garters of this class of knit goods in which the loops of the knitted fabric are extensible and contractible both longitudinally of the band as well as crosswise thereof and so suspend the clasp from the band as to take advantage of such compound elasticity.

In the accompanying drawings, Figure 1 is a perspective view of a gentleman's garter embodying my improvements. Fig. 2 shows diagrammatically the manner of forming the knit goods of which the leg-band is made, the loops being shown in their normal condition. Fig. 3 shows the appearance of the loops when strain is applied longitudinally to the leg-band. Fig. 4 shows how the loops will appear when they are stretched laterally. Fig. 5 is a perspective view of the seamless knit tubular fabric from which the leg-band may be formed. Fig. 6 is a perspective view of another style of garter containing my improvements. Fig. 7 is a similar view of still another style of garter made in accordance with my invention. Fig. 8 shows how the leg-band may be made of two strips of knit goods stitched together along their longitudi-

nal edges instead of being made from a seam-less knit tube.

The clasp A may be of any preferred construction. The one shown is well known and extensively used and need not be specifically described. The suspending device B may be a cord, as shown in Fig. 1, of non-elastic or elastic material, and is preferably circular in cross-section; but any other suitable well-known device for suspending the clasp from the leg-band may be employed. The band C in Fig. 1 is provided at one end with a hook c, adapted to engage the cord B in the usual way and with a loop a through which the cord B extends. It is also provided with an adjustable slide b, by means of which the length of the band may be regulated. These features as just described are all of usual construction; but the band C is made in a new way.

Heretofore such leg-bands have usually been made of elastic webbing having the rubber threads running longitudinally of the band, while no elasticity is given to the band crosswise, and therefore when strain is applied to the band diagonally or "on the bias" there is no compound yielding of the fabric as in my improved band. It is also common to make the leg-band of material having no elasticity or resiliency either longitudinally or crosswise. Preferably my improved leg-band is made of seamless tubular knit goods X, such as shown in Fig. 5—that is to say, the inner and outer layers of the band are connected at their edges, but not connected at any other places. One layer of the fabric can, therefore, move relatively to the other layer, and no stitching to unite the layers with each other is required. Furthermore, perfectly smooth longitudinal edges are produced, which add to the comfort of the garter. The band, however, may be made in the manner shown in Fig. 8—i.e., instead of being made from a seamless knit tube, as shown in Fig. 5, it may be composed of two strips of knit goods stitched along their longitudinal edges. In this construction also one layer of the fabric can move relatively to the other.

The knitted loops a of the fabric are of the usual form in knit goods, but are made sufficiently loose to permit them to be drawn or lengthened longitudinally of the band in the manner indicated in Fig. 3 or to be widened in

the manner shown in Fig. 4. The yarn possesses inherent elasticity, which, in connection with the resiliency of the goods, causes the fabric to assume its normal condition, as shown in Fig. 2, when strain is withdrawn. Preferably mercerized cotton is used in the construction of the fabric, but wool, silk, or other material may be employed. In view of the fact that the fabric is elastic and resilient both longitudinally and crosswise the band will readily adapt itself to the shape of the leg when under strain and under all other conditions. The fabric is soft and may be used next the skin without discomfort and without danger of slipping.

In Fig. 6 I have shown another type of garter, the general form of which is well known. In this instance the suspending device B is made of the knit goods, being preferably in one piece with the leg-band, which is of knit goods of the kind hereinbefore specified.

In Fig. 7 the suspending device B is in the form of a loop adapted to loosely encircle the leg and is made in one piece with the leg-band.

Obviously the details of construction may

be varied. Other kinds of clasps, fasteners, and suspending devices may be used and the form of the leg-band may be varied, but should in all cases be made of knit goods having the characteristics hereinbefore specified.

I disclaim, broadly considered, a leg-band or garter made of knit goods; but so far as I am aware it is new with me to combine such a leg-band with a hose-supporter clasp in such manner that a downward pull on the clasp exerts a strain on the fabric of the leg-band, which causes it to expand both longitudinally and crosswise.

I claim as my invention—

A garter comprising a leg-band and a clasp suspended therefrom, the leg-band being made from knit goods having elasticity and resiliency both longitudinally and crosswise of the band.

In testimony whereof I have hereunto subscribed my name.

GEORGE H. PHELPS.
